REVERSIBLE LONGWALL MINER

Joseph F. Joy, Pittsburgh, Pa., assignor to Joy Manufacturing Company, Pittsburgh, Pa., a corporation of Pennsylvania

Application July 12, 1951, Serial No. 236,291

19 Claims. (Cl. 262—9)

This invention relates to mining machines and more particularly to a reversible longwall miner for cutting and dislodging the coal of a solid coal seam.

In a reversible longwall miner it is desirable to move the machine rapidly back and forth along the longwall face during the cutting and dislodging operation and to provide cutting and dislodging mechanism for rapidly removing the dislodging coal onto a face conveyor. Due to the rapid rate of operation of the machine it is desirable to provide feeding means which may rapidly move the machine through relatively long distances without interruption irrespective of the direction of operation of the machine. The present invention contemplates improvements over known types of longwall miners in that the above desirabilities are attained in an improved and extremely effective manner.

An object of the present invention is to provide an improved reversible longwall miner. Another object is to provide an improved cutting and dislodging mechanism for a longwall miner. Yet another object is to provide improved feeding means for a machine of the above character whereby the machine may be rapidly moved in either direction along the longwall face. A further object is to provide improved coal breaker means for dislodging the coal as cutting progresses. A still further object is to provide improved cutting means comprising parallel superimposed cutter bars and improved coal breaker means carried by the upper cutter bar for dislodging the core of coal cut by the cutter bars as the machine is moved along the face. Still another object is to provide an improved mining machine having an improved arrangement and combination of parts. These and other objects and advantages of the invention will, however, hereinafter more fully appear.

In the accompanying drawings there is shown for purposes of illustration one form which the invention may assume in practice.

In these drawings:

Fig. 1 is a top view of a reversible longwall miner constructed in accordance with a preferred illustrative embodiment of the invention.

Fig. 2 is a side elevational view of the miner shown in Fig. 1.

Fig. 3 is an enlarged vertical section taken on line 3—3 of Fig. 1 and illustrating details of the cutting and dislodging mechanism.

Fig. 4 is an enlarged detail sectional view taken in the plane of Fig. 3, showing the automatic coal breaker means.

Fig. 5 is a detail cross section taken on line 5—5 of Fig. 4, showing the breaker disc.

Fig. 6 is an enlarged horizontal sectional view taken substantially on line 6—6 of Fig. 2.

Fig. 7 is a horizontal sectional view taken substantially on line 7—7 of Fig. 2.

Figs. 8 and 9 are diagrammatic views respectively showing the miner operating in opposite directions along a longwall coal face of an underground coal mine.

2

Fig. 10 is an enlarged detail vertical section taken substantially on line 10—10 of Fig. 1, showing details of the feeding means.

Fig. 11 is a diagrammatic view showing the machine in operating position in a mine with the machine moving from right to left along a longwall coal face, and illustrating the associated face conveyor and roof jack mechanism.

The improved reversible longwall miner is generally designated 1 and generally comprises a machine frame 2 movable in an endwise direction along a longwall coal face and carrying midway between its ends a laterally projecting cutting and dislodging mechanism, generally designated 3. The machine frame 2 comprises end frame sections 4 and 5 having plane bottom surfaces 6 slidable over the floor of the mine and rigidly connected together by an intermediate frame section 7. The frame sections 4 and 5 respectively carry motors 8 and 9 which serve to drive the cutting mechanism and providing power sources for the machine feeding means as later described. The cutting mechanism comprises parallel superimposed kerf cutters 10 and 11 projecting at right angles from the intermediate frame sections 7 and comprising upper and lower horizontal plane cutter bars 12 and 13 about the margins of which endless cutter chains 14 and 15 are respectively guided for orbital circulation in parallel horizontal paths. The cutter chains on the cutter bars are circulated orbitally in relatively opposite directions and the lower cutter chain 15 is driven by the motor 8 while the upper cutter chain 14 is driven by the motor 9.

The motor 8 has its power shaft 17 (see Fig. 7) horizontally disposed and extending longitudinally of the machine and secured to the inner end of the power shaft is a spur pinion 18 which meshes with and drives a spur gear 19 journaled on bearings 20 supported by a parallel longitudinally extending shaft 21. The shaft 21 is journaled in bearings 22 suitably supported within the machine frame and the gear 19 is connectable to the shaft 21 by a conventional sliding toothed clutch 23. Secured to the inner end of the shaft 21 is a beveled pinion 24 meshing with and driving a beveled gear 25 (see also Fig. 3) secured to the upper end of a vertical shaft 26. The shaft 26 is suitably journaled within bearings 27 supported within the intermediate frame section 7 and keyed to the lower end of the shaft 26 is a chain sprocket 28 which engages and drives the endless cutter chain 15 of the bottom cutter bar 13.

The motor 9 has its power shaft 30 axially aligned with the motor shaft 71 and secured to the inner end of the motor shaft 30 is a spur pinion 31 which meshes with and drives a spur gear 32 journaled on bearings 33 supported by a parallel longitudinally extending shaft 34. The shaft 34 is suitably journaled within bearings 35 carried within the machine frame and has fixed to its inner end a beveled pinion 36 meshing with a beveled gear 37 (see also Fig. 3). The beveled gear 37 is secured to the lower end of a vertical shaft 38 suitably journaled in bearings 39 carried by the intermediate frame section 7. Keyed to the upper end of the shaft 38 is a chain sprocket 40 which engages and drives the upper cutter chain 14. A similar sliding toothed clutch 41 serves to connect the gear 32 to the shaft 34, and the clutches 23 and 41 are provided with suitable shipper yokes 42 having suitable operating handles 42' conveniently arranged exteriorly of the machine frame at its top. From the foregoing it is evident that when the motors 8 and 9 are running and the clutches 23 and 41 are connected, the endless cutter chains 14 and 15 may be rapidly circulated in their orbits in relatively opposite directions.

Each of the endless cutter chains comprises a series of chain blocks 43 pivotally connected by strap links 44 and

the chain blocks have conventional sockets for receiving the shanks of conventional shank type cutter bits 45. Set screws 46 are provided for securing the bit shanks within the block sockets and these set screws may be loosened to permit removal of the bits from the block sockets and to permit reversal of the bit on the blocks, all in a well-known manner.

The parallel superimposed kerf cutters are adapted to cut parallel horizontal kerfs in the coal of the solid coal seam and as cutting progresses a coal breaker means, generally designated 50, carried by the upper kerf cutter, acts on the projection or core of coal formed between the kerfs to dislodge the core. This coal breaker means is arranged within an appropriately shaped recess 51 formed within the upper cutter bar within the orbit of the cutter chain 14 and the coal breaker means arranged within this recess comprises a frame 52 pivoted at 53 on a horizontal pivot pin 54 supported by brackets 55 on the top cutter bar. This vertically swingable frame has a longitudinal bore 56 which has rotatably mounted therein a spindle 57 provided with worm gear teeth 58 engageable by a worm 59 whereby the spindle 57 may be manually rotated within its bore. The spindle 57 has an enlarged cylindrical portion 60 which supports bearings 61 on which a guide roller 62 is journaled and suitable dirt seals 63 engage the roller and the cylindrical portion 60 at the opposite sides of the bearing 61 to keep out dirt from the bearings. Projecting longitudinally from the cylindrical portion 60 is an eccentric portion 64 supporting bearings 65 on which a rotary disc cutter or breaker wheel 66 is journaled and the bearings for this disc are provided with similar dirt seals 67. This disc rotates about an axis extending generally lengthwise of the top cutter bar. Thus, when the spindle 57 is rotated in its bore the eccentric 64 may be moved arcuately to vary the location of the rotary disc 66 thereby to enable penetration of the disc at different distances into the core of coal depending upon the mining conditions encountered. The teeth of the worm gears are self-locking and serve to maintain the disc in the desired adjusted position. The pivoted frame 52 has lateral lugs 67^a (Figs. 1 and 5) which project within the cutter bar at the sides of the recess 51 intermediate the top and bottom plates of the cutter bar for limiting the swinging movement of the frame in vertical planes with respect to the cutter bar while permitting limited freedom of movement of the frame about its pivot as the guide roller 62 of the breaker means travels along the uneven bottom wall of the kerf. When the breaker disc 66 is out of contact with the underlying coal the lugs 67^a may serve to prevent the frame 52 from hanging loosely down about its pivot.

The bottom cutter bar is of greater length than the upper cutter bar and the bottom cutter chain moves in its orbit near the outer side of the machine frame, so that the dislodged coal is engaged by the outwardly moving run of the bottom chain and is moved laterally from the face and discharged laterally beyond the outer side of the frame. A U-shaped upper frame 68 secured to the frame 7 has upstanding sides 69 disposed outwardly of the path of the upper cutter chain and serves to direct the cuttings brought back from the upper kerf laterally toward the outer side of the frame.

Now referring to the improved feeding means it will be noted that arranged at the opposite ends of the machine frame and carried by the end frame sections 4 and 5 are pairs of cable winding drums 70, 71 and 72, 73 arranged on parallel vertical axes as shown. Wound on the drums 70 and 71 respectively are feeding cables 74 and 75 while wound on the drums 72 and 73 respectively are guiding cables 76 and 77.

Each of the cable winding drums 70, 71 and 72, 73 is driven by a hydraulic motor 78 having fixed to the lower end of its power shaft 79 (see Fig. 10) a spur pinion 80 meshing with a spur gear 81 fixed to the drum. The motors 8 and 9 provide the power sources for the drum driving means and each motor drives a fluid pump 82.

which supplies liquid under pressure to the drum driving motors. The feed cables 74, 75 and 76, 77 are adapted to be extended longitudinally in opposite directions from the opposite ends of the machine frame and serve to feed the machine rapidly back and forth along the face and to guide the machine during the mining operation. By the provision of a pair of identical cable winding drums at each end of the machine it is possible to extend one cable to a suitable anchor in advance of the other so that when one cable nears its limit of operation the other cable may take over thereby to avoid the interruptions present when a single feed drum is employed.

The end frame sections 4 and 5 of the machine frame have at their inner sides suitable supporting surfaces for a transposable guard or retaining plate 83 which projects laterally from the machine frame along the trailing side of the bottom cutter chain for retaining the dislodged coal in the path of the chain 15 whereby the latter may convey the loose coal laterally away from the coal face toward the face conveyor. This transposable guard is rigidly secured in position on the frame as by screws and may be readily transposed from one side of the bottom cutter bar to the other depending upon the direction of operation of the machine.

The driving motors 8 and 9 for the cutter chains are respectively provided with suitable starting and reversing switches provided with control levers 84 and 85. The hydraulic system associated with the pumps 82 may include suitable liquid supply tanks and control valve devices whereby the motors 78 for driving the cable winding drums may be operated as desired. These hydraulic motors 78 may be reversible so that the cables on the drums may be paid out as well as wound in by the drums.

In Figs. 8, 9 and 11 the longwall miner is shown in operating position in a miner and Fig. 11 shows the miner together with the associated face conveyor 90 and the roof jack mechanism 91. This face conveyor and jack mechanism may be similar to those disclosed in my pending application, Serial No. 24,574, filed May 1, 1948, now matured into Patent No. 2,714,505, dated August 2, 1955, although evidently, various other types of conveyors and jack mechanisms may be employed if desired. In Fig. 11, the longwall face is designated F and parallel roadways or passageways at the ends of the face are designated R. The superimposed cutter bars are dumped laterally into the coal at the right hand end of the face with the machine extending into the right hand roadway, and as the machine is advanced along the face by the feed cable of one of the forwardly located feed drums the machine is concurrently guided by one of the cables of the rearwardly located drums. In Fig. 11, the feed cable 74 is shown nearly completely wound in by its drum with the feed cable 75 in position to take over the feed of the machine from the cable 74 and, in like manner, the guiding cable 76 is shown nearly completely paid out from its drum with the cable 77 in position to take over the guiding function of the machine. As the superimposed cutter bars are moved laterally along the coal face a projection or core of coal, designated C in Fig. 3, is being broken down from the face by the breaker means 50. The roller 62 of the breaker means runs in the kerf cut by the upper cutter chain in engagement with the bottom wall of the kerf and the breaker disc 66 cuts into the upper portion of the core of coal between the kerfs near its point of attachment with the solid seam to apply a splitting force to the core along lines generally parallel to the coal face thereby to dislodge fragments of the core as cutting progresses. The longer bottom cutter chain 15 and its cooperating guard 83 serve to move and direct the dislodged coal laterally from the face toward the face conveyor 90. In Fig. 9 the machine is shown cutting from left to right and, irrespective of the direction in which the machine is operated, when the machine reaches the end of the face the cutter bits are reversed on their respective

cutter chains and the motors 8 and 9 are reversed to effect reverse drive of the chains.

The feeding and guiding cables are extended to jacks located at different distances along the coal face as shown in Figs. 8, 9 and 11, so that when one feed cable is wound in by its drum and one guiding cable is completely paid out, the other feeding and guiding cables may take over to effect feeding and guiding of the machine without interruption in the machine movement. As the coal is mined out the walking jacks 91 may be advanced toward the face in the manner shown at the right in Fig. 11.

As a result of this invention an improved reversible longwall miner is provided having improved features of construction whereby the coal of a solid coal seam may be rapidly mined out in an extremely efficient manner. By the provision of the parallel superimposed cutter bars and the particular cutter chain arrangement and the associated breaker means carried by the upper cutter bar the coal may be rapidly cut to form a core between the parallel kerfs and the core may be rapidly dislodged from the coal face as cutting progresses. The improved coal breaker means is not only efficient in operation but is also relatively simple and compact in design. By the provision of the improved feeding and guiding means the machine may be fed and guided during its operation along the coal face without the need for interruption due to the repositioning of the cable jacks. These and other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine comprising parallel superimposed narrow elongated kerf cutters movable in a direction extending transversely of their lengths for cutting parallel kerfs in a solid coal seam to form a horizontal projection of coal between the kerfs, and coal breaker means carried by the top kerf cutter for dislodging fragments of said coal projection as cutting progresses, said breaker means including a rotary breaker disc journaled to rotate freely about an axis extending generally lengthwise of said upper kerf cutter and having a sharpened circular penetrating edge, and an adjustable mounting carried by said upper kerf cutter and including an element on which said disc is journaled and mounted to move in vertical planes relative to said upper kerf cutter for changing the vertical position of the disc-axis with respect to said upper kerf cutter to vary the splitting action of said disc on the coal projection, said mounting confining said disc-axis in all positions of movement of said disc in vertical planes extending lengthwise of said upper kerf cutter.

2. A mining machine comprising parallel superimposed kerf cutters for cutting parallel kerfs in a solid coal seam to form a horizontal projection of coal between the kerfs, and coal breaker means carried by the top kerf cutter for dislodging fragments of said coal projection as cutting progresses, said breaker means including a rotary breaker disc journaled to rotate freely about an axis extending generally lengthwise of said upper kerf cutter and having a sharpened circular penetrating edge and a support pivotally mounted on said upper kerf cutter to swing in a vertical direction relative thereto and on which said rotary breaker disc is journaled.

3. Coal breaker means as set forth in claim 2, wherein in said pivoted support has a bore in which a spindle is rotatably mounted and wherein an eccentric is provided on said spindle and means is supported by said eccentric for journaling said disc thereon, and means is provided for rotating said spindle to move said eccentric arcuately

thereby to vary the operating position of said disc with respect to said upper kerf cutter.

4. A coal breaker means as set forth in claim 2, wherein in a guide roller is mounted on said swingable support and engages the bottom wall of the upper kerf for guiding said disc during the breaking operation.

5. A mining machine comprising an elongated machine frame movable in an endwise direction rectilinearly along the face of a coal seam in parallelism with the face, core cutting means projecting laterally from said frame at right angles to the longitudinal axis of said frame and comprising parallel superimposed kerf cutters for cutting parallel kerfs in the coal to form a core of coal between the kerfs, said cutters each comprising a horizontal plane cutter bar having an endless cutter chain guided for orbital circulation about its margin, the bottom kerf cutter being of greater length than said upper kerf cutter and having its chain travel in the opposite direction from the upper cutter chain and extending in its orbit to the side of the machine frame remote from the coal face, and means cooperating with the upper kerf cutter for dislodging fragments of said core of coal as cutting progresses, said chain of said longer bottom cutter moving the dislodged coal laterally away from the coal face beyond the outer side of said frame, said frame providing an open space at said side thereof remote from the coal face, said bottom chain discharging the dislodged coal into said space remote from the coal face as the machine is advanced along the face.

6. A mining machine as set forth in claim 5, wherein a guard is mounted on said frame and extends laterally from the inner face side of said frame along the trailing side of said bottom cutter chain for confining the dislodged coal in the path of the latter whereby the dislodged coal is directed toward said space for discharge laterally from the outer side of said frame.

7. In a mining machine of the character disclosed, a coal breaker comprising a rigid horizontal support movable laterally in a horizontal kerf formed in a solid coal seam, a frame pivotally mounted on said support, and a coal breaker disc freely rotatably mounted on the outer portion of said pivoted frame to turn about an axis at right angles to the frame pivot axis.

8. A coal breaker as set forth in claim 7, wherein means is provided for adjusting the operating position of said disc with respect to said pivoted frame.

9. A coal breaker as set forth in claim 8 wherein means is provided for maintaining the axis of rotation of said disc parallel to the major axis of said support while in the different adjusted positions thereof.

10. A coal breaker as set forth in claim 9 wherein said adjusting means comprises an eccentric mounting for said disc.

11. A coal breaker as set forth in claim 7, wherein a guide roller is journaled on said pivoted frame with its axis in parallelism with the disc axis and located on said frame intermediate the frame pivot and said disc.

12. In a mining machine of the character disclosed, core cutting means comprising parallel narrow elongated kerf cutters for cutting parallel kerfs in the coal of a solid coal seam to form a core of coal between said kerfs, and breaker means carried by one of said cutters including a breaker element for applying a splitting force to the core of coal near its point of attachment with the solid seam, and an adjustable mounting structure including an element carried by said one of said cutters and on which said breaker element is mounted, said adjustable element mounted for movement relative to said kerf cutters for adjusting said breaker element in vertical planes with respect thereto to vary the depth of penetration of said breaker element in the core thereby to vary the splitting action of said breaker element on the coal.

13. A mining machine as set forth in claim 12, wherein said movable element of said mounting structure and said breaker element are located with respect to said one of said kerf cutters so that said breaker element applies the

splitting force to the core of coal along lines extending generally at right angles to the longitudinal axes of said kerf cutters.

14. In a mining machine including a horizontal plane cutter bar having an endless cutter chain guided for orbital circulation about its margin, said bar having an opening therethrough within the orbit of said chain, and a coal breaker device mounted on said cutter bar in said bar-opening and including an armlike frame pivoted at one end to swing in vertical planes about a transverse axis located near the rear wall of said opening and a rotary breaker journaled at the opposite end of said armlike frame to revolve about an axis extending generally lengthwise of said bar at right angles to said frame pivot axis.

15. A mining machine as set forth in claim 14 wherein an adjustable mounting structure is provided for said rotary breaker on said armlike frame for adjusting said rotary breaker in a vertical direction relative to said armlike frame to vary the vertical position of said rotary breaker with respect to said cutter bar thereby to vary the depth of penetration of said breaker with respect to the material to be broken.

16. In combination, a horizontal plane cutter bar having an endless cutter chain guided for orbital circulation about its margin for cutting a horizontal plane kerf in a mine vein, a rotary breaker, a mounting structure for said breaker on said cutter bar and disposed within the orbit of said chain for limited movement in vertical planes with respect to said bar and a roller carried by said mounting structure for guiding said breaker as it moves within the kerf.

17. In combination, a narrow elongated horizontal kerf cutter for cutting a horizontal kerf in a mine vein, and mineral breaker means carried by said kerf cutter for dislodging fragments of the mineral of said vein as cutting progresses, said breaker means including a rotary breaker wheel projecting from the bottom of said cutter and journaled on said cutter to rotate freely about an axis extending generally lengthwise of said cutter, and a floating mounting structure carried by said kerf cutter and on which said breaker wheel is journaled, said mounting structure having limited floating movement in vertical planes relative to said cutter, said mounting structure confining the axis of said wheel in a longitudinal vertical plane extending lengthwise of said cutter.

18. A combination as set forth in claim 17 wherein said mounting structure for said breaker wheel comprises

an element having floating movement relative to said cutter to provide for limited freedom of movement of said wheel in vertical planes with respect to said cutter and confining the wheel-axis in one of such vertical planes, said cutter providing means for limiting such floating movement of said element in either direction.

19. A mining machine comprising a narrow elongated horizontal kerf cutter movable in a direction extending transversely of its length for cutting a horizontal kerf in a solid coal seam, and coal breaker means carried by said kerf cutter for dislodging fragments of coal beneath said kerf as cutting progresses, said breaker means including a rotary breaker disc journaled to rotate freely about an axis lying in a vertical plane extending generally lengthwise of said kerf cutter in parallelism with the major axis of the latter, said disc having a sharpened circular penetrating edge and an adjustable mounting structure carried by said kerf cutter and on which said disc is journaled, said mounting structure including a disc-supporting element mounted to move in vertical planes relative to said kerf cutter for changing the vertical position of said disc with respect to said kerf cutter to vary the splitting action of said disc on the coal, said mounting structure confining the disc-axis in a vertical plane extending lengthwise of said kerf cutter.
